UNITED STATES PATENT OFFICE

THOMAS K. CREAL, OF WARREN, PENNSYLVANIA

DESIGN FOR A CABINET FOR GAME APPARATUS

Application filed November 2, 1931. Serial No. 41,597. Term of patent 14 years.

To all whom it may concern:

Be it known that I, THOMAS K. CREAL, a citizen of the United States, residing at Warren, in the county of Warren and State of Pennsylvania, have invented a new, original, and ornamental Design for a Cabinet for Game Apparatus, of which the following is a specification, reference being had to the accompanying drawing, forming part thereof.

The design is illustrated in a view showing the cabinet in perspective.

I claim—

The ornamental design for a cabinet for game apparatus, as shown.

THOS. K. CREAL.
